UNITED STATES PATENT OFFICE.

HARRY BENNETT, OF LATROBE, PENNSYLVANIA.

BEATING-ROLL FOR PAPER-PULP OR OTHER ENGINES.

No. 858,256.

Specification of Letters Patent.

Patented June 25, 1907.

Application filed August 23, 1906. Serial No. 331,806.

To all whom it may concern:

Be it known that I, HARRY BENNETT, a citizen of the United States, residing at Latrobe, in the county of Westmoreland and State of Pennsylvania, have invented certain new and useful Improvements in Beating-Rolls for Paper-Pulp or other Engines, of which the following is a specification.

This invention relates to beating rolls for paper-pulp or other engines.

Heretofore rolls of the present character have been constructed to secure the bars and heads together by means of rings or bands encircling the roll, the rings or bands being shrunk or otherwise secured in place upon the roll. Another mode has been to employ blocks between the bars in combination with the rings or bands. In the use of these rings or bands, it has been customary to form slots or notches in the ends of the bars and sometimes intermediate the ends thereof. The formation of slots or notches in the bars greatly reduces their strength, especially at their points of connection with the heads, resulting in breakage of the bars, and sometimes, considerable damage to other parts of the engine. Further, the rings or bands become displaced with the result that the bars and other parts of the roll have been broken. If the rings or bands become displaced, and blocks are employed between the bars, they also become dislodged. When these mishaps occur, the machinery is not only broken but considerable time is lost in making repairs, and sometimes, new machinery is necessary.

It is the aim of my invention to overcome these and other defects in the present type of beating engine rolls used in paper or other mills.

It will therefore be understood that my invention resides in effecting a positive locking connection between the heads of the roll and the bars without the use of blocks, rings, bands, or any other form of separate or supplemental means, my locking means being preferably part and parcel of certain of the elements constituting the roll.

Another object is to provide a simple, inexpensive, durable and efficient device of the character stated.

With the above and other objects in view, the present invention consists in the combination and arrangement of parts hereinafter more fully described, illustrated in the accompanying drawings, and particularly pointed out in the appended claims.

In the drawings: Figure 1 is a longitudinal sectional view of my improved roll, the dotted lines indicating a bar in position with respect to the heads prior to its longitudinal movement into interlocking engagement with the latter; Fig. 2 is a transverse sectional view; and Fig. 3 is a detail perspective view of one of the grinding bars.

Referring now more particularly to the accompanying drawings, the reference character 1 indicates a disk or other shaped end heads, and 2 an intermediate head preferably of the same formation as the end heads. If desired, this intermediate head may be eliminated from the structure. All the heads are cast or otherwise formed of metal or any other suitable material. The heads are mounted upon a shaft 3 or other suitable bearing and are connected by the grinding bars 4. Each head has sockets 5 in its periphery arranged to aline with the sockets of the other heads to receive the grinding bars 4. The outer ends of the sockets are contracted with respect to the inner ends thereof for a purpose presently understood.

To assemble the parts, the sockets of the heads are arranged to aline, and a bar is inserted into corresponding alining sockets with its series of projections 6 adjacent the heads, as shown in dotted lines in Fig. 1. When the bar is thus disposed it is moved or driven in any suitable manner longitudinally of the roll to force its projections tightly into the enlarged base portions or inner ends of the sockets whereby the bar is held so firmly in its seats that when once seated it is not liable to accidental endwise play in its seats. In other words, when the bar is once seated it is not allowed the slightest movement in its seats, but is held firmly therein against endwise or other play, until it is desired to remove it from its seats when it may be driven longitudinally out of its seats. All the bars are secured in the heads in the same manner, resulting in the tapering projections being wedged tightly in their sockets against accidental endwise displacement. When desired, the bars may be readily removed for cleaning or for other purposes.

It will be understood that the grinding bars may be formed in any shape desired and that they may be composed of any suitable material. It will also be understood that each bar has two, three or more tapering projections according to the number of heads embodied in the roll. Another feature to be

appreciated is that the bars may be moved longitudinally of the roll in either direction to effect the permanent interlocking thereof with the heads. To permit of this longitudinal movement of the bars in either direction of the roll is the reason why I illustrate the projections tapering in the same direction.

I obtain a positive locking connection between the bars and heads without the use of rings or any other separate or supplemental means, and without reducing the strength of the bars, my improved locking means being cast or otherwise formed integrally with the bars. If preferred, the smaller end of the tapering projections 6 may lie, flush with the edge of the corresponding bar to obviate a shoulder. This modification is too obvious for illustration.

If desired I may employ the tie-rods 7, between the heads, providing the tie-rods with right and left hand screw-threads, thereby obviating the use of nuts. It will be seen that the screw-threads of the tie-rods are not exposed to acids when the wheel is in use, and obviously, I may employ other means for connecting the rods 7 to the heads.

What is claimed is:

1. A beating roll comprising heads and removable bars having means formed therewith to lock the bars to the heads against accidental endwise play.
2. A beating roll comprising heads and bars having longitudinally tapering projec-

tions for interlocking connection with the heads to prevent accidental endwise play of the bars.

3. A beating engine roll comprising heads, and having tapering socket and projection interlocking connection with the heads to prevent accidental endwise play of the bars.

4. A beating engine roll comprising heads having recesses in their peripheries, and bars having tapering projections for interlocking connection in the recesses of the head, the projections of each bar tapering longitudinally of the bars.

5. A beating engine roll comprising heads, bars having interlocking engagement with the heads, and screw-threaded rods connecting the heads, the rods having their threads confined within the heads.

6. A beating roll comprising heads and removable bars constructed and arranged for interlocking connection with the heads to prevent accidental endwise and lateral play of the bars.

7. A bar of the character described comprising a body provided with spaced, longitudinally tapering locking projections.

In testimony whereof I have signed my name to this specification in the presence of two subscribing witnesses.

HARRY ^{his} BENNETT.
